UNITED STATES PATENT OFFICE.

WILLIAM E. WATERMAN, OF BOSTON, MASSACHUSETTS, ASSIGNOR TO WAITT & BOND INC., OF ROXBURY, BOSTON, MASSACHUSETTS, A CORPORATION OF MAINE.

MACHINE FOR MARKING CIGARS.

1,172,184.

Specification of Letters Patent. Patented Feb. 15, 1916.

Application filed December 30, 1914. Serial No. 879,662.

To all whom it may concern:

Be it known that I, WILLIAM E. WATERMAN, a citizen of the United States, and resident of Boston, in the county of Suffolk 5 and State of Massachusetts, have invented certain new and useful Improvements in Machines for Marking Cigars, of which the following is a specification.

This invention relates to machines for impressing on cigars, by means of dies or other marking devices, characters indicating the manufacturer's name, trade-mark, etc., the cigars being moved progressively and subjected successively to the action of the dies.

15 The object of the invention is to provide certain improvements in a machine of this character looking to the rapid and effective marking of the cigars without liability of injuring the wrappers by the branding operation.

The invention consists in the improvements which I will now proceed to describe and claim.

25 Of the accompanying drawings forming a part of this specification: Figure 1 represents a side elevation of a marking machine embodying my invention; Fig. 2 represents a top plan view of the same; Fig. 3 represents an enlarged elevation showing portions of the machine; Fig. 4 represents a top plan view showing a portion of the cigar carrier, the die carrier hereinafter referred to being removed; Fig. 5 represents a section 30 on line 5—5 of Fig. 1; Fig. 6 represents a section on line 6—6 of Fig. 2; Fig. 7 represents a plan view of the under side of the cigar carrier; Fig. 8 represents a view partly in section and partly in elevation, showing a modification; Fig. 9 represents a 35 bottom plan view of a portion of the cigar carrier support represented by Fig. 8.

The same reference characters indicate the same or similar parts in all the views.

45 The fixed frame of the machine comprises a horizontal bed 12, which supports the upper stretch of the endless traveling cigar carrier hereinafter described, said bed being located above and supported by a horizontal platform 13 through suitable intermediate supporting uprights 14, 15. The platform 13 is provided at its ends with fixed bearings 16, in which the journals of idle carrier pulleys 17 are mounted.

50 The cigar carrier is composed of a plurality of trough-shaped members 18, each

formed to support a cigar 19. The members 18 are connected by rivets 20 (Fig. 7) with flexible carrying belts 21 (Figs. 5 and 7), adapted to run on the pulleys 17, the upper stretches of said belts being in sliding contact with the support 12. The members 18 may be connected in an endless series by any other suitable means. A gage 22 located beside a portion of the upper stretch of the cigar carrier enables the operator to properly locate the cigars in the troughs of the carrier members 18, one end of each cigar abutting against the gage 22, as indicated by Fig. 2.

55 The cigar carrier may be driven by any suitable means. In the embodiment of the invention here shown said carrier is driven by an electric motor 23 (Fig. 1) mounted on the platform 13, a shaft 24 journaled in bearings in the uprights 14 and having a 60 pulley 25 which is connected by a belt 26 with the armature shaft of the motor, a shaft 27 journaled in other bearings in the uprights 14 above the shaft 24 and connected with the latter by gears 28 and 29, 65 and a gear 30 on the shaft 27 meshing with gear or rack teeth 31 (Figs 6 and 7) formed between recesses in the sides of the members 18. Any other suitable mechanism may be 70 employed to drive the cigar carrier.

75 32 represents a rotary die carrier, which as here shown is a cylinder the shaft of which is extended from opposite ends of the cylinder to form journals 33. The die carrier is provided with radially projecting dies 34 adapted to mark, print or brand the desired inscriptions on the cigars 19, the die carrier and dies being preferably heated by suitable means, such as an electric heating unit 35 centrally located in the carrier, 80 so that the dies print by searing the wrappers of the cigars. The heating means may be omitted however, and the dies may be otherwise adapted to mark, brand or print the cigars. The dies 34 are detachably 85 inserted in radial slots formed for their reception in the carrier 32, as indicated by Figs. 5 and 6, and may be confined in said slots by any suitable means.

90 One of the die carrier journals 33 is provided with a gear 36 meshing with a gear 37 on the shaft 27, said gears constituting 95 connections between the die carrier and the cigar carrier whereby said carriers are moved in unison so as to present the cigars 100 110

successively to the dies. The die carrier is so mounted that it is free to rise and fall, but is confined against horizontal movement so that the dies bear with a yielding pressure on the cigars, the pressure being due to the weight of the die carrier and being adjustable or regulable by means herein-after described. The die carrier journals 33 rotate in bearings 38, which are vertically movable and provided with standards 39 adapted to move vertically in guides 40 and 41 (Fig. 3) formed on fixed supporting brackets or standards 42 attached to the frame of the machine. Each standard 39 is provided between the bearings 40 and 41 with an abutment 43 which rests on a supporting spring 44, the latter being supported by the lower bearing 41. The springs 44 yieldingly support the die carrier and 20 dies and reduce the downward pressure of the lowest or acting die on a cigar so that said die is not subjected to more than the necessary pressure. The abutments 43 are preferably adjustable to vary the tension of 25 the springs 44, said abutments being nuts, and the standard 39 being screw-threaded to engage the internal threads of the abutments or nuts. If desired, springs 44^a, shown by dotted lines in Fig. 3, may be 30 interposed between the upper guides 40 and the abutments 43, said springs exerting a downward pressure on the abutments and die carrier. When the abutments 43 are 35 adjusted separately the pressure of the upper springs 44^a is increased and that of the lower springs 44^a is increased and that of the lower springs 44 is decreased, and vice versa. Provision is therefore made for nicely regulating the pressure of the dies on the cigars. 40 It will now be seen that provision is made for enabling the weight of the die carrier to exert any desired degree of yielding pressure on the cigars.

The bearings 38 are preferably open 45 above the journals 33, said bearings having spaced-apart extensions 38^a between which the journals 33 may be moved vertically to retract the die carrier from the cigar carrier. Means are provided where- 50 by the operator may raise or retract the die carrier whenever this is desirable, said means including levers or lever arms 45 and 46, both rigidly attached to a rockshaft 47 which is journaled in fixed uprights 48. Said lever arms have slots 49, one of which is shown by Fig. 3, through which the journals 33 extend so that upward swinging movements of the lever arms 45 and 46 will cause a rectilinear upward movement of the 55 journals and die carrier, the journals being guided by the bearing extensions 38^a.

The lever arm 46 is extended to form an outwardly projecting arm 46^a, which is connected by a rod 50 (Fig. 1) with an arm 60 65 51 attached to a rockshaft 52 which is jour-

naled in fixed bearings at the base of the machine frame. To said rock-shaft is attached a treadle lever 53 having a foot-piece 54, the depression of which raises the die carrier through the described 70 connections.

To steady the motion of the die carrier and prevent loose or idle movements thereof as might be due to backlash I provide means for resisting the rotation of the 75 die carrier through one of its journals 33, said means comprising brake shoes 55 bearing on opposite sides of one of the journals 33, as shown by Figs. 3 and 5. The lower brake shoe is attached to a lower lever 56, and the upper brake shoe is attached to an upper lever 57. Said levers have shorter arms projecting in one direction from the journals, and connected by a bolt 58. The longer arms of said levers project in the opposite 80 direction and are connected by a bolt 59 having a head which bears on the upper lever 57 and a nut 60 bearing on and supported by an ear 61 formed on the lifting lever arm 45. The lower end of the bolt 59 85 is threaded and provided with a nut 62 forming an abutment for one end of a spring 63 the other end of which bears on the ear 61. When it is desired to steady the rotation of the die carrier, the nut 62 90 is turned to increase the compression of the spring 63. Said spring acts through the bolt 59, lever 57, bolt 58, and lever 56 to press the brake shoes 55 against the journal 33 on which they bear. Said rotation 95 resisting means is vertically movable with the die carrier and is therefore not affected by changes of position of the latter. The portion of the cigar carrier under the die carrier is confined against upward movement from the support 12 by fixed overhanging ears 64 (Fig. 5). The cigars are 100 prevented from upward displacement by overhanging guard strips 66 (Figs. 3, 4 and 5).

It will now be seen that I have provided means for applying a regulated pressure of the dies to the cigars, the pressure being capable of nice adjustment so that injurious indenting of the cigars by the dies or marking devices and breakage of the wrappers may be readily guarded against.

I do not limit myself to the means above described for maintaining a yielding pressure of the dies on the cigars. Instead of mounting the journals of the die carrier in movable bearings, said journals may be mounted in fixed bearings and the portion of the cigar carrier support under the die carrier may be adapted to yield, as in the modification illustrated by Figs. 8 and 9. In this modification 32^a represents a die carrier the journals of which are, or may be, mounted in fixed bearings. The cigar carrier support is composed of a fixed portion 12^a and 110 115 120 125 130

a vertically movable portion 12^b which supports the cigar carrier members 18 under the die carrier. The supporting portion 12^b is a plate having at its central portion downwardly projecting studs 67 engaged with levers 68 pivoted at 69 to fixed ears and are pressed upwardly by springs 70 interposed between the support portion 12^a and the rear arms of the lever 68. The springs 70 exert a constant upward yielding pressure on the movable support portion 12^b so that the members of the cigar carrier on said portion are adapted to yield downwardly.

The terms "brand" and "branding" are used as synonyms of print or mark, and printing or marking, and are not to be understood as limiting the invention to a machine in which the branding, printing or marking instrumentalities are heated to sear the cigar wrappers.

Having described my invention, I claim:

1. A cigar-marking machine comprising a rotary die carrier having dies and end journals, means coöperating with said journals to prevent horizontal movements and permit vertical movements of the die carrier so that the dies are pressed yieldingly downward by the weight of the carrier, a traveling cigar carrier, a support for the latter, and connections between the two carriers whereby they are moved progressively in unison to present cigars successively to the dies.

2. A cigar-marking machine comprising a rotary die carrier having dies and end journals, means coöperating with said journals to prevent horizontal movements and permit vertical movements of the die carrier so that the dies are pressed yieldingly downward by the weight of the carrier, means for yieldingly opposing downward movement of the die carrier, a traveling cigar carrier, a support for the latter, and connections between the two carriers whereby they are moved progressively in unison to present cigars successively to the dies.

3. A cigar-marking machine comprising a rotary die carrier having dies and end journals, means coöperating with said journals to prevent horizontal movements and permit vertical movements of the die carrier so that the dies are pressed yieldingly downward by the weight of the carrier, adjustable means for yieldingly opposing downward movement of the die carrier, a traveling cigar carrier, a support for the latter, and connections between the two carriers whereby they are moved progressively in unison to present cigars successively to the dies.

4. A cigar-marking machine comprising a rotary die carrier having dies and end journals, vertically movable bearings for said journals, springs supporting said bearings and yieldingly opposing their downward movement, a traveling cigar carrier, a sup-

port for the latter, and connections between the two carriers whereby they are moved progressively in unison to present cigars successively to the dies.

5. A cigar-marking machine comprising a rotary die carrier having dies and end journals, vertically movable bearings for said journals, springs supporting said bearings and yieldingly opposing their downward movement, means for regulating the resilience of said springs, a traveling cigar carrier, a support for the latter, and connections between the two carriers whereby they are moved progressively in unison to present cigars successively to the dies.

6. A cigar-marking machine comprising a rotary die carrier having dies and end journals, vertically movable bearings for said journals having elongated vertical shanks, fixed upper and lower guides in which said shanks are vertically movable, spring abutments secured to said shanks between said guides, springs interposed between the lower guides and the abutments and yieldingly opposing downward movement of the bearings and die carrier, a traveling cigar carrier, a support for the latter, and connections between the two carriers whereby they are moved progressively in unison to present cigars successively to the dies.

7. A cigar-marking machine comprising a rotary die carrier having dies and end journals, bearings for said journals vertically elongated to permit the upward displacement of the journals and die carrier, a traveling cigar carrier, a support for the latter, connections between the two carriers whereby they are moved progressively in unison to present cigars successively to the dies, and means for vertically displacing the journals and die carrier to retract the lowest die from the cigar carrier.

8. A cigar-marking machine comprising a rotary die carrier having dies and end journals, bearings for said journals vertically elongated to permit the upward displacement of the journals and die carrier, a traveling cigar carrier, a support for the latter, connections between the two carriers whereby they are moved progressively in unison to present cigars successively to the dies, a pair of levers fulcrumed on fixed supports and engaged with the journals, a treadle, and connections between the treadle and the said levers whereby the latter may be moved to vertically displace the journals and die carrier to retract the lowest die from the cigar carrier.

9. A cigar-marking machine comprising a rotary die carrier having dies and end journals, means coöperating with said journals to prevent horizontal movements and permit vertical movements of the die carrier, so that the dies are pressed downwardly by the weight of the carrier, a traveling

cigar carrier, a support for the latter, connections between the two carriers whereby they are moved progressively in unison to present cigars successively to the dies, and 5 adjustable means movable vertically with the carrier for opposing the rotation thereof.

10. A cigar-marking machine comprising a rotary die carrier having dies and end journals, bearings for said journals vertically elongated to permit the upward displacement of the journals and die carrier, a traveling cigar carrier, a support for the latter, connections between the two carriers whereby they are moved progressively 15 in unison to present cigars successively to the dies, a pair of lifting levers fulcrumed on fixed supports and engaged with the journals, means for moving said lifting levers, brake shoes bearing on opposite sides

of one of said journals, upper and lower 20 levers attached to said shoes and having shorter arms projecting in one direction from said journal and longer arms projecting in the opposite direction therefrom, a bolt connecting said shorter arms, a bolt 25 engaged with the longer arm of the upper lever and supported by an abutment on one of said lifting levers, and a spring acting through said bolts and upper and lower levers to press the brake shoes against said 30 journal.

In testimony whereof I have affixed my signature, in presence of two witnesses.

WILLIAM E. WATERMAN.
